UNITED STATES PATENT OFFICE.

OTTO C. SCHWARZ, OF NEW CHICAGO, INDIANA.

WINDOW-SASH.

1,331,726.

Specification of Letters Patent. Patented Feb. 24, 1920.

Application filed September 17, 1917. Serial No. 191,726.

To all whom it may concern:

Be it known that I, Otto C. SCHWARZ, a citizen of the United States, and a resident of New Chicago, in the county of Lake and State of Indiana, have invented certain new and useful Improvements in Window-Sashes; and I do hereby declare that the following is a full, clear, and exact description thereof, reference being had to the accompanying drawings, and to the characters of reference marked thereon, which form a part of this specification.

This invention relates to a novel window sash and more particularly, the invention relates to a novel combined swinging and sliding window sash in which one of the sash members is hinged at one side to the window frame jamb so as to be swung toward and from its closed position in the manner of a door, while the other sash member is mounted to slide in the swinging member in the manner of an ordinary sash.

The purpose of the invention is to provide an economical, light and exceedingly simple sash construction of the character described, which may be mounted in place by relatively unskilled labor and also to provide a sash structure by which the window frame may be washed from the inside of the window, and which also permits of a wide range of ventilating opening at the window.

The invention consists in the combination and arrangement of the parts shown in the drawings and described in the specification, and is pointed out in the appended claim.

In the drawings:—

Figure 1 is an inside elevation of a window sash and mounting embodying my invention.

Fig. 2 is a vertical section on the line 2—2 of Fig. 1.

Figs. 3 and 4 are cross sections taken on the respective lines 3—3 and 4—4 of Fig. 1.

Fig. 5 is an enlarged vertical section of one of the sliding sash stiles, and the associated parts, taken on the line 5—5 of Fig. 6.

Fig. 6 is a cross section on the line 6—6 of Fig. 5.

Fig. 7 is a perspective detail of a portion of the upper rail of the swinging sash.

Fig. 8 is an enlarged section on the line 8—8 of Fig. 5.

As shown in the drawings:—

10, 10 designate the jambs of the window

frame, 11 the lintel and 12 the sill thereof. 13, 13 designate the sides of the window box and 14, 15 designate, respectively, the top and bottom members of the box. 15 60 designates as a whole the swinging window sash which is hinged on one of the jambs 10 by any suitable form of hinges 16 to swing toward and away from the other jamb. It may be fastened in place by fasteners 17 of 65 any suitable design. Said swinging sash comprises vertical stiles 18, 18, upper and lower rails 19, 20, respectively, and a central rail 21 (Fig. 2). 22 designates a pane of glass which extends across and is supported 70 in the usual manner by the stiles and upper and central rails of the swinging frame.

23 designates, as a whole, a sliding sash which is mounted to slide in the swinging sash. It comprises upright stiles 24, 24 and 75 the upper and lower rails 25, 26, respectively. It supports a pane of glass 27 which normally closes the lower part of the window.

The jambs 10 of the window frame and the lintel thereof are recessed at 29 to receive the swinging sash, and the stiles and upper rail of said swinging sash are provided with extensions 30 which overlap the jambs and the lintel to produce weather tight joints. The lower rail of the swinging sash fits inside the sill 12 and said rail and sill are shaped to provide a drip groove; and said lower rail is formed with a lip or extension 31 to fit against the inner face of the sill, as shown in Fig. 2. The said stiles 90 18 of the swinging sash are provided at their inner edges with vertical tongues 32 which extend a distance beyond said edges, and are provided just exterior to said tongues with vertical grooves 33 (Fig. 6). 95

The stiles of the sliding sash are provided with vertical grooves 34 into which fit the tongues 32 of the stiles of the swinging sash and on which tongue said sliding sash slides. The flanged portions 35 of the 100 sliding sash stile in the rear of the grooves 34 fit in the grooves 33 of the swinging sash stiles. The portions 36 of said sliding sash stiles extending beyond the grooves 34 overlap the inner faces of the swinging sash 105 stiles. The tongue and groove connections of the stiles of the sliding and swinging sashes thus formed produce effective weather tight joints between said swinging and sliding sashes.

In order that the sliding sash may be completely detached from the swinging

sash, the upper rail 19 of the swinging sash is composed of two parts or members one of which, 38, is detachably fitted to the inner flat face of the permanent rail member, 5 as by the screws 39. Said detachable rail member 38 is provided at its ends with tongues 40 which fit in interlocking engagement with notches 41 at the upper ends of the rails 18 of the swinging sash stiles. By removing the screws 39, the rail member 38 may be lifted upwardly out of its seat and, when so removed, the sliding sash may be freely slid upwardly away and detached from the swinging sash.

15 In order that the sliding sash may be readily adjusted to different heights in the swinging sash and locked in such adjusted positions, an automatic sash stop is provided. It is shown most clearly in Figs. 5 and 6, and its position indicated in Fig. 1. It comprises a series of vertically spaced lugs 42, 42 at the lateral face of one of the sliding sash stiles which are adapted to cooperate with a suitable stop 47 carried by the adjacent stile of the swinging sash. These lugs are herein shown as formed by folding together the intermediate portions of metal strap or band 43, which is attached in any suitable manner, as by screws 44, to the lateral faces of one of the stiles of the sliding sash. Preferably the said strap 43 is seated in a groove 45 that is formed in the overlapping portion 36 of said stile inside the swinging sash stile.

30 The adjustable stop 47 is mounted on a plate or casting 46 that is fastened to the inner face of the adjacent stile of the swinging sash near the top of the sliding sash when the latter is in its lower position, and the swinging stop is mounted to swing on a pivot 48 carried by said plate. A stop lug 49 formed on the laterally inner edge of said plate constitutes means to limit the downwardly swinging movement of said stop 47, this position of the stop being a horizontal 45 position. A second lug 50 on the upper edge of said plate 46 serves as a means to limit the upwardly swinging movement of said stop 47.

50 With this construction it will be apparent that when the sliding sash is raised the engagement of one of the lugs 42 with the stop 47 will serve to swing the stop upwardly out of the path of said lug until the said stop has swung upwardly a sufficient distance to permit the lug to pass the same, whereupon the stop drops back on the stop lug 49. Thus said stop operates automatically to permit the sash to be raised as high as desired with 55 in the limit of its adjustment, and in cooperation with the lug 49 serves to positively hold the sliding sash in a given position of adjustment. When the sash is to be lowered said sash is raised sufficiently to permit the 60 stop 47 to be raised out of the path of the

lugs 42, and at this time the stop may be thrown backwardly against the lug 50, whereupon the sash is free to descend.

With the construction described, a number of advantages become apparent. First, it 70 will be seen that both sides of the window are readily available to wash the glass panes when the swinging sash is swung inwardly. Furthermore, the sliding sash may be operated in the usual manner of an ordinary 75 sliding sash to more or less open the lower part of the window, there being no impediment to the usual movement of such sliding sash. Moreover, a full or partial window opening may be secured by the use of the 80 swinging sash beyond or less than that afforded by the raising of the sliding sash, by opening the swinging sash more or less and locking it in any position. Another advantage of the construction is that all of the 85 parts are simple to manufacture and to mount in the frame. This feature of the construction particularly adapts the sash to country houses and other places where skilled labor is not readily available for the purpose of hanging the sash.

The stop arm 47 may be locked from swinging upwardly so as to thereby limit the open movement of the sash by means of a locking device which is best shown in Fig. 8. 95 It comprises a plunger 55 which extends through and is slideable in the stop arm mounting plate 46. It is provided at its rear end with a nut or other form of shoulder 56 between which and the plate is 100 interposed a spiral expansion spring 57 that normally holds the plunger inwardly. The plate is provided with a socket piece 58 which fits within a suitable opening in the stile of the swinging sash to receive the inner 105 end of the plunger and said spring. The outer end of the plunger is provided with a hook 60 which, when the stop arm is intended to operate automatically to permit the lugs 42 to pass the same, is turned downwardly in the full line position shown in Fig. 8. When the stop arm is to be locked from rising the plunger is pulled outwardly such distance as to bring the end of the hook 60 inside of the plane of the stop arm, 110 whereupon said plunger may be turned to swing the hook to the position indicated in dotted lines in Fig. 8. The plunger is then released and the spring 57 will carry the hook over the stop arm and thus lock the 120 stop arm from rising.

It will be understood that the structural details are capable of some variations within the spirit and scope of the invention, and that the invention is not limited to the details shown except as to claims wherein said details are specifically set forth, and as imposed by the prior art.

I claim as my invention:

The combination with a swinging sash, 130

having means to hinge it to a window frame, said sash comprising upright stiles and a top, a bottom and a central rail, with the stiles longitudinally grooved in their proximate faces, of a sliding sash having laterally extending tongues engaging said grooves of the swinging sash stiles, the upper rail of the swinging sash comprising a fixed member and a removable member, the latter in the plane of the grooves of said swinging sash stiles, with means to removably attach the removable member to the fixed member,

whereby when the removable member is removed the sliding sash may be moved upwardly away from the swinging sash.

15

In testimony, that I claim the foregoing as my invention I affix my signature in the presence of two witnesses, this 6th day of September A. D. 1917.

OTTO C. SCHWARZ.
